Patented April 4, 1905.

UNITED STATES PATENT OFFICE.

WILLIAM R. SCHAFFER, OF FORT LEE, NEW JERSEY, ASSIGNOR TO L. STRAUS & SONS, OF NEW YORK, N. Y.

DESIGN FOR A GLASS VESSEL.

SPECIFICATION forming part of Design No. 37,389, dated April 4, 1905.

Application filed February 23, 1905. Serial No. 247,057. Term of patent 7 years.

To all whom it may concern:

Be it known that I, WILLIAM R. SCHAFFER, a citizen of the United States, residing in the city of Fort Lee, county of Bergen, and State of New Jersey, have invented a new and original and ornamental Design for Glass Vessels, the same being disclosed in the accompanying drawings, in which—

Figures 1 and 2 are side elevations, and Fig.

3 is a top plan view, of a glass vessel, showing my design.

I claim—

The ornamental design for a glass vessel, as shown.

WILLIAM R. SCHAFFER.
